UNITED STATES PATENT OFFICE.

ISRAEL J. EVIN, OF ALTOONA, PENNSYLVANIA.

DRESS GUARD AND CHAIR HOLDER.

Application filed October 1, 1920. Serial No. 414,109.

To all whom it may concern:

Be it known that ISRAEL J. EVIN, a citizen of the United States, residing at Altoona, in the county of Blair and State of Pennsylvania, has invented certain new and useful Improvements in Dress Guards and Chair Holders, of which the following is a specification.

This invention relates to an improved 10 clothing guard to be used in connection with shoe polishing stands of the type usually found in modern shoe shining parlors.

A primary object is to provide a simple and adjustable guard device that may be 15 readily placed in position between the foot rest and the seat to prevent the catching of garments on the foot rest as the patron descends from the seat. In that connection it is proposed to provide a device which will 20 entirely span or bridge the space between the foot rest and the seat position, regardless of whether the seat may be in the form of a chair, bench, or the like, thereby to prevent the likelihood of portions of patrons' 25 clothing being caught and torn, and at the same time rendering the invention susceptible of a wide range of use in connection with various types and styles of equipment.

A further and more specific object of the 30 invention is to provide a clothing guard whose parts are capable of facile adjustment and are adapted to installations where either a portion of the seat or the platform on which the seat is supported may constitute or furnish a point of attachment for 35 a portion of the guard.

With the above and other objects in view which more readily appear as the nature of the invention is better understood, the same 40 consists in the novel construction, combination and arrangements of parts, hereinafter more fully described, illustrated and claimed.

A preferred and practical embodiment of 45 the invention is shown in the accompanying drawings in which—

Figure 1 is a side elevation of a chair and foot rest of the type usually employed in shoe shining parlors.

50 Figure 2 is a front elevation of the type of chair shown in Figure 1.

Figure 3 is a view similar to Figure 2 showing a bench instead of a chair.

55 Figure 4 is a detail elevation of the embodiment of the improved dress guard

showing the same attached to both the platform and the chair leg.

Figure 5 is a horizontal sectional view of the construction shown in Figure 4, the same showing the guard device in plan. 60

Figures 6 and 7 are respectively a side elevation and top plan view of a modified form of the device made out of tubular parts.

Similar reference characters designate 65 corresponding parts throughout the several figures of the drawings.

In carrying the present invention into effect it is proposed to provide a device that will adequately guard against the catching 70 of the patron's clothing on the foot rest as he steps down from the seat. In that connection it will be observed as shown in the drawings, that the invention is particularly intended for use with modern shoe polish- 75 stands which involve a stepped platform, the lower step constituting a support for the foot rest while the upper step provides a support for the chair, bench, or other form of seat. In its primary aspect 80 the present invention involves a guard device comprising a bar 10 or its equivalent which may be positioned between the foot rest and the said post to prevent garments from catching on the foot rest, and in that 85 respect the present invention represents a carrying forward of the idea set forth in my co-pending application No. 397349, filed July 19, 1920.

Referring more specifically to the drawings it will be observed that the present bar 10 of the guard device is adapted to engage with the foot rest, supporting platform, or seat, and to that end the guard bar and its attaching parts are made relatively extensible and adjustable to enable the device to meet the requirements in various installations. 90

As will be observed from Figures 4 and 5 for example, the guard bar 10 is provided at one end with a chair clamp 11, while the opposite end is provided with a foot rest clamp 12 which may be secured to the bar by means of the bolt and the wing nut 13 or its equivalent. The intermediate portion of the guard bar 10 may be provided with a platform attaching bracket 14, the upper end 15 of which may be conveniently engaged by the end 16 of the chair clamp 105 110 to hold it in position. As will be observed

from Figure 4 the said chair clamp 11 has a relatively adjustable engagement with the bar 10 through the medium of the openings 17.

5 Figures 6 and 7 of the drawings show a modified type of guard bar which may consist of a tubular portion 20 adapted to telescopically receive at one end a portion of a foot rest clamp 21, while the opposite end 10 23 may telescopically receive the shank 24 or a seat clamp 25, and the said shank of the clamp may be held in place by the set screw 27 or its equivalent. If desired the tubular guard 20 may be provided with a slot 28 to permit the screw 27 to slide longitudinally therein, when it is necessary, to move the seat S toward and from the foot rest R.

In the embodiment shown in Figures 6 and 20 7 the equivalent of the support engaging bracket 14 is found in the tubular standard 31 which may be formed with an eye at its top end to receive the tubular member 20, while the lower end telescopically receives 25 the post 32 of a clamp 33 which may be secured to the edge of the step of the platform by a screw 34 or its equivalent. Also, as shown, a screw 35 or the like may be employed for causing the tubular standard 31 to engage the post 32. In all forms of the invention it will be apparent that the guard member or bar may extend from the foot rest R into the zone of the seat position as clearly indicated in Figures 1, 4 and 6. In that way 30 35 the guard member insures against accidental engagement of garments with the guard bar which might otherwise have the same disastrous effect as engaging with the foot rest.

The present application, so far as it relates 40 to the feature of supporting the guard members 10 and 20 from the platform for the seat, is a continuation in part of my former application #397349, filed July 19, 1920.

Without further description it is thought 45 that the many features and advantages of the invention will be readily apparent, and it will of course be understood that changes

in the form, proportion, and minor details of construction may be resorted to without departing from the spirit of the invention or 50 the scope of the appended claims.

I claim:

1. A clothing guard for shoe-blacking stands including the combination with a seat and a foot rest on the stand, of a support 55 carried by the stand, a guard bar carried by the support and spanning the distance between the foot rest and the seat.

2. A clothing guard for shoe-blacking stands including the combination with a seat 60 and a foot rest, of a support carried by the stand, a guard bar carried by the support and spanning the distance between the seat and the foot rest, and clamping means carried by the opposite ends of the guard bar 65 for engaging with the foot rest and seat.

3. A clothing guard for shoe-blacking stands including the combination with a seat and a foot rest on the stand, of a support carried by the stand, and an extensible guard 70 bar carried by the support and spanning the distance between the seat and the foot rest.

4. A clothing guard for shoe-blacking stands including the combination with a seat and a foot rest on the stand, of a support carried by the stand and an extensible clothing 75 guard member carried by the support and adapted to span the distance between the foot rest and the seat, said extensible guard member consisting of telescopically engaged 80 tubular members.

5. A clothing guard for shoe-blacking stands including in combination with a seat and a foot rest on the stand, a support having a clamp at one end for engaging with the stand, a clothing guard member carried by the other end of the support, a clamping member at one end of the guard member for engaging with the foot rest, and a clamping member at the other end of the guard member 90 for engaging with a leg of said seat.

In testimony whereof I affix my signature.

ISRAEL J. EVIN.
